CLAIM

The ornamental design for a golf club head, as shown and described.

DESCRIPTION

FIG. 1 is a bottom perspective view of our new design for a golf club head;

FIG. 2 is a front view thereof;

FIG. 3 is a top view thereof;

FIG. 4 is a bottom sole view thereof;

FIG. 5 is a back view thereof;

FIG. 6 is at heel view thereof; and,

FIG. 7 is a toe view thereof.

The broken line showing on the top of the hosel and the bottom surface of the golf club head are included for the purpose of illustrating unclaimed subject matter and forms no part of the claimed design.

1 Claim, 3 Drawing Sheets(56)
